UNITED STATES PATENT OFFICE.

FREDERICK W. RUBIN, OF INDIANAPOLIS, INDIANA.

DRY-KILN.

1,281,212.

Specification of Letters Patent.

Patented Oct. 8, 1918.

Application filed March 5, 1918. Serial No. 220,459.

To all whom it may concern:

Be it known that I, FREDERICK W. RUBIN, a citizen of the United States, and a resident of Indianapolis, county of Marion, and State of Indiana, have invented a certain new and useful Dry-Kiln; and I do hereby declare that the following is a full, clear, and exact description thereof, reference being had to the accompanying drawings, in which like

10 letters refer to like parts.

This invention relates to drying kilns for timber. One of the features of the invention is the provision of means for directing jets of steam through ricks of timber. A further feature of the invention is the provision of means to comingle heated air with the jets of steam so that the air and steam will travel together through the rickcd timber.

A further feature of the invention is the provision of means for reversing the direction of travel of the jets of steam and heated air so that the same may be directed upwardly through the central portion of the stack of timber and outwardly between the 25 layers of the timber, or inwardly through the layers of timber from the edges thereof and downwardly through the central portion of the stack of timber.

A further feature of the invention is the provision of means along the walls of the 30 kiln for causing a draft between the layers of the timber, said means being reversible so as to cause the air to travel in opposite directions through the layers of timber.

A further feature of the invention is the provision of means for directing the air from the draft creating device toward the heating means for the air, when the current is traveling outwardly through the layers of the timber from the central portion of the stack of timber.

A further feature of the invention is the provision of means for directing live steam into the kiln below the stack of timber to prevent the timber at the lower end of the stack, or that immediately over the heating device from becoming more intensely heated than the timbers at the upper end of the stack.

50 A further feature of the invention is the provision of means for directing the currents of air along the upper wall of the kiln and so arrange said means that the dripping from condensation will be discharged at pre-

determined points, and a further feature of 55 the invention is the provision of drains for catching the condensate and conveying the same to a discharge point and thus prevent the condensate from descending upon the stack of timber.

60 The full nature of the invention will be understood from the accompanying drawings and the following description and claims:

Figure 1 is a longitudinal vertical sectional view through the kiln showing the timber trucks in proper position as when timber is stacked thereon. Fig. 2 is a transverse vertical section through the kiln showing trucks having timber stacked thereon. 70 Fig. 3 is a detail perspective view of the means for directing the currents of air at the upper portion of the kiln and showing the means of conveying the condensate to the drain troughs. Fig. 4 is a detail perspective view showing the means of controlling the travel of the jets of steam and air at the central portion of the kiln, and Fig. 5 is a detail side elevation of the steam conveying and controlling pipe.

80 Referring to the drawings in which similar reference numerals designate corresponding parts throughout the several views. 1 indicates a kiln which is constructed in any preferred manner, the walls being preferably formed of brick and having ventilating flues 2 at intervals therein, said flues being connected with the interior of the kiln by means of ventilators 3 of the usual or any preferred form, said ventilators being employed for discharging a certain amount 85 of water laden air from the kiln, so as to constantly require a supply of fresh air and thus regulate the moisture within the kiln.

90 In kilns of this class, trackways 4 are extended longitudinally of the kiln upon which travel trucks 5, said trucks being employed for conveying timber 6 in quantities into the kiln, and as shown in Fig. 2 of the drawing the timber is so rickcd or 100 stacked upon the trucks that a vertical passageway 7 is provided at the center of the stack of timber and a series of transverse passages 8 formed in the stack of timber extending from the central passage to the 105 outer edges of the stack of timber.

In arranging the timber in this manner air and steam or other drying medium may

pass through the various passages in the stack of timber and thoroughly dry or cure the same.

In order to cause the air and steam to more readily travel through the passages in the stack of timber, a steam conveying pipe 9 is extended longitudinally of the kiln and preferably centrally below the stacks of timber, said pipe being provided at intervals with ports 10 through which the steam may escape from the pipe 9 and in order to control the travel of the steam after escaping through the ports and at the same time properly comingle the same with heated air, sleeves 11 are connected to the pipe 9 and extend at right angles to the pipe, said pipe extending through the sleeves so as to cause the sleeves to surround the ports 10, one end of the sleeves being open, while the opposite ends thereof are bifurcated to form extensions 12, which project radially from the pipe 9, whereby the air heated by the radiators 13 will be easily gathered by the extensions and comingle with the jets of steam passing through the opposite ends of the sleeves.

When the sleeves 11 and pipe 9 to which they are attached are turned to the position shown in Fig. 2, the comingled steam and heated air will pass directly into the vertical passageway 7 and upwardly through the stack of timber.

In order to cause the air and steam to travel to the upper end of the stack of timber, and to pass laterally through the horizontal passages between the timbers, a plurality of pipes 14 are arranged along the said walls of the kiln and extended to any desired height, each pipe having a plurality of nozzles 15 through which air may pass into or out of the pipes, said nozzles being arranged at the proper points for creating the desired current, and to create a suction or draft in said pipes, the lower ends thereof are brought together and connected to a fan 16, which when rotated in one direction will create a suction through the pipes and when driven in the opposite direction will cause a flow of air in the opposite direction. The fans 16 are preferably driven by steam which is conducted through the motor 17 of the fan by means of a pipe 18, one end of the pipe 18 being preferably connected with one of the ventilators 3, so that the exhaust steam may pass up the ventilating flue.

When the drying operation is first started, it has been found that the lower tiers of timber will be treated or dried more rapidly than the upper tiers, so that the timber at this point will not receive the proper amount of moisture and to obviate this objectionable feature, the pipe 18 which passes through the motor 17 is provided with a valve 19 which when turned in one direction will cause the exhaust of the motor to

pass into the kiln and as it is situated adjacent the lower tiers of the timber, will supply the proper amount of moisture for the superheated timbers.

As soon, however as the proper density of the air in the kiln has been acquired, the valve 19 is closed so as to cause the exhaust from the motor to pass through the ventilator into the ventilating flue.

When the air is drawn downwardly through the pipes 14 it is discharged from the fan 16 into the distributing pipe 20 which extends parallel with the trackway 4 and is provided with nozzles 21 which are preferably inclined as shown in Fig. 2 of the drawing so as to discharge the air below the timber and directly against the radiators 13. By positioning the nozzles 21 in this manner they are in position to collect the heated air directly from the radiators when the current of air is being directed upwardly and outwardly through the nozzles 15.

The fresh air is introduced into the kiln in any suitable manner, but preferably through an air duct 22 which is positioned longitudinally of the kiln below the radiators, the air when discharged through the air duct passing directly upwardly between and around the radiators.

As shown in the drawings there are three nozzles in each pipe section 14, but it will be understood, of course that this number may be increased or decreased according to the height of the kiln, thus adapting the same for use in connection with piles of lumber of various heights.

In view of the fact that the heated air is charged with steam, a condensate is naturally formed on the roof or top wall of the kiln and said condensate will naturally drip back on the pile of timber and injure the timber if no provision is made to collect and dispose of the condensate and likewise the current or travel of the air adjacent the roof of the kiln will become sluggish if no means is provided to increase the current at this point.

To this end, therefore, means is suspended from the top wall or ceiling 23 of the kiln for increasing or forming a draft at this point, and for gathering any condensate that may form on the ceiling, comprising brackets 24, which are suspended a distance from the ceiling by hangers 25, the brackets 24 being substantially in corrugated formation to provide inclined sections 26 and substantially vertical sections 27, the inclined sections 26 receiving and supporting flat strips 28, preferably of wood, the width of said strips being such that the upper edges thereof will slightly overhang the lower edge of the next succeeding strip, although said strips are spaced a distance apart, to form passageways 29 between the strips.

In order to create a current of air adjacent to the ceiling, one half of the strips, or those at one side of the center of the kiln are inclined in one direction, while the strips 5 at the opposite side of the center of the kiln are inclined in the opposite direction, so that one half of the air current passing through the passageways between the strips will be directed to one side of the kiln, while the remaining portion of the current will be directed to the opposite side of the kiln.

In order to prevent the condensate gathered by the strips 28 and on the ceiling 23 from descending upon the timber, a gutter 15 or trough 30 is positioned immediately below the lower edge of each strip 28, said gutters being suspended in any suitable manner from the brackets 24, and as the condensate drips from the inclined strips it will descend into the gutters and be conveyed to a discharge point and thus prevent the same from coming in contact with the timber.

In operation, jets of steam are first discharged through the ports 10 by opening the 25 valve 31 in the pipe 9, the passage of the steam through the sleeves 11 creating a suction in the extensions 12 and thus drawing the air through the extensions and mixing the same with the steam. This mixture after 30 leaving the sleeves 11 passes upwardly through the vertical passageway 7 and spreads it through the transverse passages 8 to the outer edges of the timber, and during certain stages of the drying operation the 35 fans 16 are operated to create or increase the travel of the air through the timber so that the parts thereof will be properly cured or dried.

It is also necessary at times, at a certain period in the drying operation to reverse the direction of the travel of the draft through the timber in which instance the pipe 9 carrying the sleeves 11 is rotated until the open end of the sleeve 11 is directed downwardly, which is accomplished through the medium of a handle 32, and when the pipe is so turned the operation of the fan 16 is reversed, thus drawing the air through the nozzles 21 and discharging the same through the nozzles 15, in which event the current of air will travel first through the transverse passages 8 from the outer edges of the stack of timber to the vertical passageway 7, and thence downwardly and outwardly at the lower end of the stack of timber.

By placing the heaters directly above the air duct 22, as shown, the air is heated as it passes into the kiln and it will also be seen by discharging the air from the nozzles 21, or from the sleeves 11 when said sleeves are pointing downwardly, the used air will be reheated and kept at a substantially uniform temperature throughout the confines of the kiln, thus drying the timber at the upper

end of the stack at the same rate that the timber is dried at the lower end of the stack, or in other words, each piece of timber is dried the same throughout the extent of the stack.

If it is found that the lower pieces of timber are becoming overheated, as when the drying process is first started and before the air is properly charged with the steam, the exhaust from the motors employed for driving the fans 16 may be discharged into the kiln at a point adjacent or below the lower end of the stack of timber, thus retaining the moistened condition of the timber at this point in uniformity with the timber at the upper portion of the stack.

The invention claimed is:—

1. The combination with stacks of timber arranged to provide passages therethrough, of means for controlling a drying current 85 and causing the same to pass through said passages in either direction.

2. Means for drying timber, comprising heating elements for heating air, means to direct jets of steam into passages formed 90 in the stacks of timber, means to commingle heated air with the jets of steam, and means to cause a draft through the passages in the stack of timber to cause the steam and heated air to reach all of the timber in the 95 stack.

3. A dry kiln for drying timber, comprising heating means extending below stacks of timber in which are formed passages, and means at the sides of the stacks of timber 100 for creating a draft through the passages in the stacks of timber from top to bottom thereof.

4. A dry kiln for timber, said timber being stacked in tiers and having passages therethrough, means below the stacks of timber for directing commingled air and steam into the passages, means along the sides of the stacks of timber for creating a draft through the passages in the stacks of timber, and means to reverse the travel of the draft through said passages.

5. In a dry kiln for timber, the combination with stacks of timber arranged to form vertical and transverse passages therethrough, of means at the sides of the stacks of timber for creating a current through said passages in either direction.

6. In a dry kiln for timber, the combination with stacks of timber having passages formed therethrough, of pipes extending vertically of the stacks of timber, and means to cause a suction or draft through said pipes whereby a current will be caused to travel in either direction through the passages in the stacks of timber.

7. The combination with stacks of timber assembled to form passages therethrough, of a steam conveying pipe below the stacks of timber having ports there-

through, means surrounding said ports for directing the jets of steam into the passages in the stack of timber, means to comingle air with the jets of steam, and means to rotate said steam conveying pipe to change the course of travel of the air and steam through said passages through the timber.

8. The combination with stacks of timber arranged to form passages therethrough, of means to direct steam and air through said passages, comprising a steam conveying pipe having ports therethrough, sleeves through which the pipe extends, said sleeves surrounding the ports, lateral tubular extensions at one end of the sleeves through which air is drawn into the sleeves, and means to rotate the pipe for reversing the direction of travel of the air and steam through the passageways.

9. In a drying kiln a plurality of pipe sections adapted to extend vertically along the sides of stacks of timber, nozzles in said pipe sections, a fan arrangement for drawing or forcing air through said pipe sections and nozzles, a motor for running said fan, means to control the exhaust of said motor to discharge the same at different points, and means to reverse the rotation of said motor and fan to change the direction of travel of the current through the pipe sections.

10. In a dry kiln for timber, the combination with means for directing steam and air through stacks of timber, of means suspended above the stacks of timber for directing currents adjacent the roof of the kiln and for collecting and conveying condensate.

11. In a dry kiln for timber, brackets suspended from the ceiling of said kiln, flat strips carried by said brackets and spaced apart and supported at an angle, and means at the lower edges of the strips for collecting and conveying condensate.

12. The combination with a ceiling of a dry kiln, of brackets suspended from said ceiling, said brackets having inclined sections, strips resting upon said inclined sections and held at an angle thereby, and means below the lower edge of each strip for receiving and conveying condensate from the strips.

13. The combination with a ceiling of a dry kiln, of brackets suspended from said ceiling, said brackets having inclined sections and substantially vertical sections, flat strips resting against the inclined sections, said strips being spaced apart to form air passages, and means to receive and convey condensate discharged from said strips.

In witness whereof, I have hereunto affixed my signature.

FREDERICK W. RUBIN.
